UNITED STATES PATENT OFFICE.

CLAUDE H. FREESE, OF LOS ANGELES, CALIFORNIA.

DEODORIZING DEVICE.

1,211,306.

Specification of Letters Patent.

Patented Jan. 2, 1917.

Application filed July 19, 1916. Serial No. 110,245.

To all whom it may concern:

Be it known that I, CLAUDE H. FREESE, a citizen of the United States, residing at Los Angeles, in the county of Los Angeles and State of California, have invented a new and useful Deodorizing Device, of which the following is a specification.

My invention relates to deodorizing devices, and more particularly to that class of such devices in which a deodorizing liquid is fed to absorbent material having an evaporating surface.

The principal object of my invention is to produce a device of the class described of simple form and construction having an evaporating surface which may be readily increased or diminished to meet the particular requirements of the use to which the device is put in each case.

Referring to the drawings, which are for illustrative purposes only: Figure 1 is a perspective view of a device embodying a form of my invention. Fig. 2 is a vertical, sectional view of the device shown in Fig. 1, the liquid container being shown in full lines. Fig. 3 is a sectional plan view on line x^3-x^3 of Fig. 2.

The device is designed in the form shown to be supported on the wall, and consists of a plate 5 of sheet metal having the central portion raised as shown at 6, thereby leaving a space between the central portion of the plate and the wall to which the plate is secured by means of a screw 7. The plate 5, in the lower portion thereof, is provided with two openings or perforations 8 adapted to receive the bent ends 9 of a circular band 10, the ends 9 terminating in outwardly extending flanges or toes 11 which engage the back of the plate along one edge of the openings 8.

The band 10 is preferably made of spring metal and when the ends 9 of the band are inserted in the openings 8 the ends of the band tend to move away from each other, thereby engaging the edges of the openings 8 as heretofore described. The band 10 forms a support for a cup 12 which has a rolled edge 13 engaging over the band 10. Supported in the cup 12 is a cylindrical sleeve 14 of porous material, such as plaster of Paris, or similar material, the sleeve 14 being dished at the top as shown at 15 to form a seat and support for a bottle 16. The bottle 16 is placed in inverted position, the body portion thereof resting on the

sleeve 14, and the neck 17 of the bottle extending downwardly into the sleeve, the height of the sleeve being such that the mouth 18 of the bottle is slightly above the bottom 19 of the cup 12, as shown in Fig. 2. The bottle 16 is supported in upright position on the sleeve 14 by means of a band 20 of similar form and construction to the band 10, the ends 21 of the band 20 extending through openings 22 in the plate 5 and toes or flanges 23 engaging the back of the plate.

25 designates a series of rings of porous material, the lowermost ring 25 being seated in the cup between the walls of the cup and the sleeve 14, and other rings of the same character being placed one above another as shown in Fig. 2; it being understood that a greater number of rings may be placed one above another, as indicated in dotted lines 75 in Fig. 2, for the purposes hereinafter described.

The device is used in the following manner: Deodorizing liquid is placed in the bottle 16 and the same is inverted and placed 80 upon the sleeve 14 in the cup 12, as shown. The liquid in the bottle slowly drains therefrom to the bottom of the cup 12 where it is taken up by the porous material of the sleeve 14 and rings 25. The liquid taken up 85 by the sleeve and rings is evaporated from the surface of the same exposed to the atmosphere, the extent of which surface may be regulated by the number of rings 25 used, the greater the number of rings the greater 90 amount of evaporating surface, resulting in the more rapid feed of the liquid from the bottle 16 to the cup 12.

It is understood that the device may be quickly taken apart and removed from the 95 plate 5, the bands 10 and 20 being removed by pressing the ends of the respective bands together, thereby releasing the toes on the respective bands from engagement with the plate.

100 What I claim is:

1. In combination, a supporting member, a cup supported on said member, a sleeve of porous material in said cup, a bottle supported on said sleeve in inverted position 105 thereon, the neck of said bottle extending downwardly into said sleeve with the mouth of the bottle spaced apart from the bottom of the cup, and a series of rings of porous material in said cup about said sleeve, the 110 rings being placed one above another.
2. In combination, a supporting plate hav-

ing a pair of openings therein, a band having its ends extended through said openings to support the band on said plate, a cup supported in said band, a sleeve of porous material in said cup, a bottle supported on said sleeve in inverted position, the mouth of said bottle being spaced apart from the bottom of said cup, a series of rings of porous

material in said cup inclosing said sleeve, said rings being placed one above another, 10 and means detachably secured to said plate for supporting the upper end of said bottle.

In testimony whereof, I have hereunto set my hand at Los Angeles, California, this 10th day of July, 1916.

CLAUDE H. FREESE.
